(57) **CLAIM**

The ornamental design for a rifle vented upper receiver, as shown and described.

DESCRIPTION

FIG. 1 is an isometric front view showing the right side of an embodiment of the apparatus disclosed herein;

FIG. 2 is an isometric front view showing the left side of the apparatus of FIG. 1;

FIG. 3 is a plain top view of the apparatus of FIG. 1;

FIG. 4 is a plain front view showing the right side of the apparatus of FIG. 1;

FIG. 5 is a plain end-on view of the apparatus of FIG. 1, wherein such end is located on the right side of the apparatus as shown in FIG. 3;

FIG. 6 is a plain end-on view of the apparatus of FIG. 1, wherein such end is located on the left side of the apparatus as shown in FIG. 3;

FIG. 7 is a plain bottom view of the apparatus of FIG. 1; and, FIG. 8 is a plain front view showing the left side of the apparatus of FIG. 1.

The Shading, and cross-hatching presented in the drawings are for illustration only and do not form a part of the claimed design.
